UNITED STATES PATENT OFFICE.

HENRY HUNT, OF JERSEY CITY, NEW JERSEY, ASSIGNOR TO HARTFORD CARPET COMPANY, OF HARTFORD, CONNECTICUT.

DESIGN FOR CARPET.

SPECIFICATION forming part of Design No. 12,088, dated January 4, 1881.

Application filed September 18, 1880. Term of patent 3½ years.

To all whom it may concern:

Be it known that I, HENRY HUNT, of Jersey City, in the county of Hudson and State of New Jersey, have invented a new and original 5 Design for a Carpet, of which the following is a specification.

This invention relates to a new and original design for carpets and similar fabrics; and it consists in the novel grouping and configuration of figures hereinafter more fully described.

The accompanying photograph illustrates a face view of a carpet having my new design.

Upon and over a background presenting the appearance of an interwoven or interlaced fabric stretch vine-like branches A A' A² A³ A⁴ A⁵ A⁶. These branches divide into stems and twigs ornamented with serrated leaves b b b. Upon these vine-like branches appear at intervals rosettes of varied shapes and sizes, c d e h j 15 k l, generally marking the junction of two or more branches. These branches bear also flower-like figures f, which resemble somewhat a tulip, and g, which is a conical rose-like figure, and i, showing a flower-like figure with leaves like the spokes of a wheel, and m, an oblong flower with serrated edges, and m', a flower figure with its outer leaves widely open, and n, a pendent bud-like figure. These vines and flowers are somewhat connected by branching 20 leaves and buds.

I claim—

1. The design for carpets, consisting of the tulip-like figure f, substantially as shown.
2. The design for carpets, consisting of the vine-like branches A A' A² A³ A⁴ A⁵ A⁶, substantially as shown. 35
3. The design for carpets, consisting of the figure j, substantially as shown.
4. The design for carpets, consisting of the figure e, substantially as shown. 40
5. The design for carpets, consisting of the figure e, substantially as shown.
6. The design for carpets, consisting of the figures A and j, substantially as shown.
7. The design for carpets, consisting of the figures A' and f, substantially as shown. 45
8. The design for carpets, consisting of the figures A² i c, substantially as shown.
9. The design for carpets, consisting of the figure m, substantially as shown. 50
10. The design for carpets, consisting of the figure m', substantially as shown.
11. The design for carpets, consisting of the figures A, A', A², A³, A⁴, A⁵, A⁶, a, b, c, d, e, f, g, h, i, j, k, m, m', and n, substantially as shown.

HENRY HUNT.
